UNITED STATES PATENT OFFICE.

ROBERT BURGER-WEBER, OF BURG, SWITZERLAND.

LAMELLAR CARRIAGE SPRING.

Application filed October 21, 1922. Serial No. 596,159.

To all whom it may concern:

Be it known that I, ROBERT BURGER-WEBER, a citizen of the Republic of Switzerland, residing at Burg, in the Canton of 5 Aargau, Switzerland, have invented certain new and useful Improvements in Lamellar Carriage Springs, of which the following is a specification.

The lamellar carriage-springs hitherto known, that is, those used in connection with automobiles, railway—and other carriages and vehicles, have the great drawback that in consequence of certain weather conditions, for instance through humidity, they 10 oxidize in a comparatively short time once the grease applied to the lamellar leaf-springs has dried up. The resulting increased friction between the separate leaf-springs is prejudicial to a proper play of 15 the carriage-spring, so that the shocks imparted to the carriage when in movement, instead of being absorbed by the spring, are necessarily taken up by the carriage frame and thus very often cause breakages in the 20 spring. If, therefore, the latter is not frequently taken to pieces and cleaned and greased, damage to the carriage and consequent accidents are sooner or later likely. However, the periodical dismounting of the 25 springs not only places the automobile or other carriage out of temporary use, but such dismounting is mostly difficult and causes much waste of time, for which very reasons these labours are as often as not 30 neglected. It has previously been proposed, it is true, to overcome these drawbacks by means of lubricating devices arranged laterally of the carriage-springs and causing the oil or other lubricating means to be forced 35 between the separate leaf-springs. Such devices, however, are totally insufficient, inasmuch as the lubricating means is more likely 40 to be pressed out at the sides of than into and between the leaf-springs.

The present invention has for its object 45 to avoid all the aforementioned disadvantages, the improved carriage-spring comprising a series of lamellar leaf-springs, of which each other is provided with a longitudinally disposed groove or channel adapted to communicate with a bore provided in a bolt, the latter extending through all the leaf-springs and centrally thereof, in such a manner, that lubricating means pressed 50 through the bore in said bolt is made to pass

into the grooves and between the separate leaf-springs.

In the accompanying drawings:

Figs. 1 and 2 show a longitudinal and a cross section, respectively, of the carriage-spring according to a first construction, and 55 Figs. 3 and 4 show sectional views of a modified construction.

Similar parts are designated by like references throughout the several views and in 60 the specification.

Referring to Figs. 1 and 2, the carriage-spring comprises seven leaf-springs 1, 2, 3, 4, 5, 6 and 7, of which the lower ones, as usual, are shorter than those above. These leaf-springs are held together in the known manner by a clamp or the like (not illustrated), and secured against displacement, relative 65 one to the other, by a centrally disposed bolt 8 which extends through the whole set of the 70 leaf-springs. This bolt is provided, firstly, with a bore 9 which is closed at the bottom but open at the top; secondly, with a lubricator such as, for instance, a grease-box 13 of which only the lower part is indicated; 75 and thirdly, with slots 10 which correspond 80 approximately with the cross section of the grooves in the leaf-springs 2, 4 and 6. The latter have longitudinal grooves 11 therein, these grooves gradually diminishing towards 85 each of the ends of the leaf-spring and forming with the base of the above lying leaf-spring a channel which communicates with the slots 10 and therefore with the bore 9 of the bolt 8. 90

If lubricating means is forced into the bore of the said bolt, it is made to pass through the slots 10 into the channels 11, then over the well rounded-off edges of the same in order finally to be pressed between 95 the separate leaf-springs, which, to facilitate the penetration of the oil or other grease, may be formed with lateral or oblique smaller grooves. Owing to the friction of the adjacent leaf-springs, caused by the play of the 100 whole carriage-spring during the movement of the carriage, the lubricating grease is enabled to reach even those places which, by the mere pressure under which the grease is forced into the channels, would otherwise be 105 inaccessible. In this way a thorough lubrication of the adjacent faces of the leaf-springs is effected, and a lasting of the carriage-spring made possible. The play thereof will not be affected but remains even, al- 110

- ways provided, that the lubrication is not neglected and renewed at regular intervals. Since the leaf-springs 2, 4, and 6 are weakened by the grooves 11, it will be of advantage to neutralize the weakening by making these leaf-springs somewhat thicker than those without grooves. The grooves 11 may also, if desired, contain linings, and the latter made to receive and distribute the lubricating means.
- The modification shown in Figs. 3 and 4 is distinguished from the device hereinbefore described merely by a different construction of the bolt receiving the lubricant. The bolt 8^a according to this modification, instead of having a central bore, now has two oppositely arranged grooves 12, which at the top communicate with the bore of an integral screw-threaded part 9^a adapted to receive the grease-box 13. The purpose of this construction of the bolt 8^a is to minimize as far as possible its weakening, the size of the bolt, relative to that of the spring, being of course limited.
- In place of the grooves described and shown channels of other form could be provided in the leaf-springs. By the application of my improved carriage-spring, especially on automobiles, the latter are preserved

to the utmost, the carriage-spring absorbing 30 easily all the shocks and thus warranting a smooth movement of the vehicle.

I claim:

1. In the herein-described lamellar carriage-spring, the combination, with a series of 35 leaf-springs of which every other one is provided with a longitudinally disposed groove, of a bolt mounted centrally of the leaf-springs and extending therethrough, the said bolt having a bore and slots communicating 40 with the corresponding grooves in the leaf-springs, and means to cause a lubricant to be pressed through the said bore and slots into the grooves.

2. In the herein-described lamellar carriage-spring, the combination, with a series of leaf-springs of which every other one is thicker than the adjacent leaf-spring and provided with a longitudinally disposed groove diminishing towards either end, of a 50 bolt mounted centrally of and extending through the leaf-springs, the said bolt having a central bore and lateral slots to communicate with the grooves in the leaf-springs, and means to cause a lubricant to be 55 pressed through the said bore and slots into the grooves.

ROB. BURGER-WEBER.
